UNITED STATES PATENT OFFICE.

E. J. WHITE, OF LOCKE, NEW YORK.

IMPROVEMENT IN PLOWS.

Specification forming part of Letters Patent No. 35,272, dated May 13, 1862.

To all whom it may concern:

Be it known that I, E. J. WHITE, of Locke, in the county of Cayuga and State of New York, have invented a new and Improved Plow; and I do hereby declare that the following is a full, clear, and exact description of the same, reference being had to the accompanying drawings, making a part of this specification, in which—

Figure 1 is a side sectional view of my invention, taken in the line $x x$, Fig. 2; Fig. 2, a front view of the same.

Similar letters of reference indicate corresponding parts in the two figures.

This invention relates to an improvement in that class of plows which are commonly termed "gang-plows."

The object of the invention is to obtain a simple and efficient device which may be readily manipulated and adapted to plowing at various depths, be capable of being mounted on wheels, and all so arranged as to insure an easy draft and admit of any number of plows being used at the will of the driver or operator.

To enable those skilled in the art to fully understand and construct my invention, I will proceed to describe it.

A represents a horizontal frame or platform, which is mounted on two wheels, B B', the wheel B being larger in diameter than B', in order to admit of the former running in the furrow and preserve the horizontality of the frame A. (See Fig. 2.)

C is the draft-pole, which is attached to the frame or platform A. On this frame or platform the driver's seat D is placed and six standards, E F G H I J. Through the upper part of the standard E the fulcrum-pin *a* of a lever, K, passes, to the back end of which a vertical plow-standard, L, is attached by a pivot, *b*. The standard L passes through the frame or platform A, and is allowed to work freely up and down therein. To the lower end of the standard L an ordinary plow, M, is secured in any proper way. When this plow M is not required to operate it is raised above the surface of the ground by depressing the front end of lever K and securing it in a notch in the lower part of the standard F. (See Fig. 2.)

N is a lever which has its fulcrum-pin *c* in the upper part of the standard G, and has a vertical pendent bar, O, attached to its back end. The bar O passes loosely through the frame or platform A, and has a colter, P, at its lower end, which colter is in a proper relative position with plow M to cut the sod of the furrow-slice to be turned over by said plow.

The plow M and its colter P are at the back part of the frame or platform A, and at the front part of said frame or platform there is a similar plow, Q, the standard R of which passes vertically through the frame or platform, and is connected at its upper end to the front part of a lever, S, by a pivot, *d*. The fulcrum-pin *e* of the lever S passes through the upper part of the standard H, and the front part of said lever, when the plow Q is elevated above the surface of the ground, is fitted in a notch in the lower part of the standard I. The colter T has its bar U also passing vertically through the frame or platform A, and is attached at its upper end to the front part of a lever, W, which has its fulcrum-pin *f* passing through the upper part of the upright J.

The driver from his seat D may operate any of the levers K N S W, and thereby raise either of the plows M Q and colters P T. The standards F I may be provided with a series of notches, so that the levers K S may be retained at different points and the plows M Q kept in a more or less elevated state, as may be required to plow the desired depth. By this arrangement it will be seen that one or two plows may be used at the will of the driver or operator, and the depth of the furrows regulated, as may be required, with the greatest facility, and also the depth of the cut of the colters. The front part of the frame or platform A has a gage-wheel, X, attached, which is an important feature, as it prevents the front part of the machine being drawn down under the action of the front plow, Q, and consequently prevents the back plow, M, being unduly elevated. The wheel X therefore insures the plows working a uniform depth in the soil.

Two or more plows may be used, as may be desired. I do not confine myself to any particular number.

Having thus described my invention, what I claim as new, and desire to secure by Letters Patent, is—

The plows M Q, when attached to vertical sliding standards L R, which pass loosely through the mounted frame or platform A, and are connected to adjusting-levers K S, in combination with the vertically-adjustable col-

ters P T and gage-wheel X, all arranged for joint operation, as and for the purpose herein set forth.

E. J. WHITE.
